UNITED STATES PATENT OFFICE.

MAX GARBELL, OF CHICAGO, ILLINOIS, ASSIGNOR TO GARBELL TYPEWRITER CORPORATION, OF CHICAGO, ILLINOIS, A CORPORATION OF DELAWARE.

TYPEWRITING MACHINE.

Application filed January 30, 1922. Serial No. 532,632.

To all whom it may concern:

Be it known that I, MAX GARBELL, a citizen of the United States, residing at Chicago, in the county of Cook and State of Illinois, **5** have invented a certain new and useful Improvement in Typewriting Machines, of which the following is a full, clear, concise, and exact description, reference being had to the accompanying drawings, forming a **10** part of this specification.

This invention relates to improvements in typewriting machines.

One object of the invention is to provide an efficient and simple line lock and stopping **15** arrangement for typewriters wherein the arrangement consists of few parts relatively inexpensive to manufacture and assemble.

Another object of the invention is to provide a line locking arrangement for the **20** platen to prevent multiple impressions when the carriage reaches the end of the normal line movement and becomes locked.

Other objects of the invention will more clearly appear from the description and **25** claims hereinafter following.

In the drawings forming a part of this specification, Figure 1 is a part vertical sectional view part elevational view of the rear portion of a typewriting machine showing **30** my improvements in connection therewith, the platen and longitudinally movable frame on which it is directly mounted being shown in central position. Figure 2 is an enlarged elevational view corresponding to Figure 1 **35** but showing the position of the parts when the platen and its frame are at the limit of the normal movement toward the left, as viewed from the back of the machine, or toward the right, as viewed from the front of **40** the machine—that is, the position corresponding to the beginning of a line of written matter. Figure 3 is a view similar to Figure 2 illustrating the position assumed by the parts when the platen and its longitudinally movable frame have set the locking mechanism which corresponds to the **45** limit of movement of the platen toward the right, as viewed from the back of the machine, or to the left, as viewed from the front **50** of the machine. Figure 4 is a view similar to Figure 3 but illustrating the platen still farther to the right, as viewed from the back of the machine, and representing the extreme limit of movement of the platen.

Figure 5 is a vertical sectional view corresponding substantially to the section line 5—5 of Figure 3. And Figure 6 is a part horizontal sectional view part top plan, the section corresponding to the line 6—6 of Figure 5. **55**

In the drawings, I have shown my improvements as applied to a typewriting machine of that class such as shown in my Patent No. 1,305,893, dated June 3, 1919, and in pending applications No. 360,598, filed February 24, 1920; No. 464,133, filed April 25, 1921; and No. 474,029, filed May 31, 1921. As shown in said patent and applications, the typewriter is of that class commonly known as a portable typewriter and is further characterized by the fact that the platen carriage (by which term is included the platen proper, the longitudinally movable frame by which the platen is directly carried and the sub-frame on which the slidable frame is supported) is readily removable from the main frame. **60**

In said drawings, the main frame of the machine is indicated at 10, the same being supported on suitable cushion pads 11, as **65** customary. The platen carriage includes a platen proper indicated at 12, and longitudinally slidable frame 13 and a sub-frame 14. The frame 13 and sub-frame 14 are provided with suitable tracks, as indicated at **70** 15—15, with anti-friction balls 16 therebetween to minimize the friction to the movement of the frame and its platen. Although the details of the removable carriage are not **75** shown, reference may be had to any one of my said pending applications. **80**

Mounted on the frame 13, and rigid therewith, is the longitudinally extending escapement rack 17 with which co-operates a gear 18 driven by a spring motor therewithin in **85** a well-known manner. The escapement mechanism shown, comprises a pinion 19 in mesh with said rack 17, the pinion being rigid with a ratchet wheel 20, as best shown in Figure 5. Said ratchet wheel 20 and **90** pinion 19 are loosely rotatably mounted on a bushing 21, which, in turn, is supported on a stud shaft 22 riveted to a bracket 23, which, in turn, is rigidly secured to the sub-frame 14. **95**

Co-operable with the ratchet wheel 20 is an escapement rocker dog 24, which is pivotally mounted on the bracket 23 by means **100**

2
of adjustable horizontally extending pivot screws 25—25, the rocker dog 24 being oscillatable about a horizontal axis parallel to the line of movement of the platen and in a plane perpendicular to the platen. Said rocker dog 24 has a single tooth 26 adapted to engage successively with the teeth of the ratchet wheel 20. Said rocker dog 24 is operated from the universal bar of the machine by means of a link 27, as shown best in Figure 5. The rocker dog 24 is normally held in its outermost position by means of a spring 28 which is interposed between it and the bracket 23, said spring 28 being mounted on a sleeve 29 which is loosely telescoped over a stud 30 carried by the bracket 23.

Pivots and slidably mounted on the rocker dog 24 is an escapement stepping dog 31, which has an elongated slot 32 pivotally and slidably mounted on a pin 33 carried by the rocker dog 24, as shown in Figures 1, 2 and 3. The stepping dog has a single tooth 34 adapted to engage the teeth of the ratchet wheel 20 successively and alternately relatively to the tooth 26.

The stepping dog 31 is spring-influenced toward the right, as viewed in Figures 1, 2 and 3, by a coiled spring 35 which is attached at one end to a depending arm 36 thereof and at its other end to a relatively fixed flange 37. With this arrangement, the rocker dog 24 is brought into engagement with a tooth of the ratchet wheel 20 when the universal bar is actuated, thereby forcing the stepping dog 31 out of engagement with the ratchet wheel temporarily and allowing the latter to be projected toward the right for the distance permitted by the slot 32. As the rocker dog 24 swings outward from the ratchet wheel 20, the tooth 34 of the stepping dog engages with the next tooth of the ratchet wheel 20 and stops the latter after it has been allowed a rotation in a clockwise direction for a distance corresponding to one tooth.

The escapement mechanism may be rendered inoperative so as to allow free movement of the platen in either direction horizontally of the machine by means of the pivoted clearing lever 38, which has a downwardly extending arm 39 adapted to depress the stepping dog 31 to an inoperative position when the lever 38 is depressed. The latter has an upwardly extending curved arm 40 which rides beneath the clearing bar 41, the latter being vertically slidably mounted on the frame 13 by means of set screws 42 passing through elongated inclined slots 43. Said clearing bar is provided with a finger 44 at the right-hand end, as viewed in Figures 1 and 2, by which said clearing bar may be depressed, thereby depressing the lever 38 and rendering the escapement mechanism inoperative. A back-

spacing pawl 45 is shown adapted to cooperate with the rack 17, said pawl 45 being operated from a link 46 by suitable means, as shown, for instance, in my said application No. 474,029.

The platen frame 13 is provided with a margin rack 47 extending horizontally and in a position above and rearwardly of the escapement rack 17. Said margin rack 47 is pivotally mounted on suitable pivots 48—48 and is adapted to be oscillated about its pivots by a finger 49. As will be understood, spring means are employed to normally hold said margin rack 48 in a vertical position.

Adjustably slidably mounted on said margin rack 48 are right and left margin stops designated A and B, the right and left being as viewed from the rear of the machine and as shown in Figure 1. Said margin stops A and B are of like construction and each preferably comprises a formed sheet metal housing 50 having a sloping top 51 with a leaf spring 52 interposed therebetween and the top edge of the margin rack 47. Said housing 50 substantially encircles the margin rack 47 and has a suitable tooth formation 53 at one end to engage with the square teeth of the rack. At its outer end, each housing 50 is provided with depending ears 54 between which is pivotally mounted a depending stop or finger 55. Each finger 55 is under the control of a coiled tension spring 56, the arrangement being such that the finger of the margin stop B cannot swing clockwise beyond the vertical position shown in Figure 1 and the finger of the other margin stop A cannot swing in a counter-clockwise direction beyond the vertical position shown in Figure 1, although each is free to swing in the opposite direction against the action of the controlling spring 56.

As shown in Figure 5, a pivot screw 57 is mounted in the outer end of the stud shaft 22. Pivots and mounted on said screw 57 is a line lock designated generally by the reference C. Said line lock C is in the form of a suitably shaped stamped plate having an upwardly extending arm 58 and a downwardly extending arm 59. Said line lock C is spring-influenced in a counter-clockwise direction by means of a light coiled spring 60 mounted on the screw 57 and having suitable engagement at its end with the arm 58 and with a pin 61 carried by the enlarged flanged end of the stud shaft 22. Said pin 61 also operates as a stop in conjunction with the arm 59 to limit the counter-clockwise rotation of the line locking element C.

The upper end of the arm 58 of the element C is bent outwardly substantially horizontally, as indicated at 58^a, so as to lie in the path of the finger 55 of the margin

stop B. The lower arm 59 of the element C is offset inwardly toward the platen, as indicated at 59^a in Figure 5 and is notched, as indicated at 62, so as to provide a right-angled tooth 63 adjacent the tooth 26 of the rocker dog. Said tooth 63 may be slightly beveled to facilitate its entrance between the rocker dog tooth 26 and the ratchet wheel 20. At its extreme lower end the arm 59 is formed with an out-turned small shoulder flange 64 which is adapted to engage with the vertically extending edge of the rocker dog tooth 26, when the line lock is operated, as shown in Figure 3.

The operation of the line lock is as follows. As the platen moves from left to right, as viewed in Figures 1 and 3, the finger 55 of the margin stop B finally engages with the out-turned flange 58^a and oscillates the locking element C against the action of the spring 60, thereby forcing the tooth 63 of the element C behind the rocker dog tooth 26 and between said rocker dog tooth and the ratchet wheel 20. This condition is illustrated in Figure 3. The limit of oscillation of the element C is determined by the shoulder flange 64 engaging with the rocker dog tooth 26. In this condition of the parts, it will be observed that the rocker dog 24 is prevented from further oscillation, and is, in fact, positively locked. Not only does this prevent further operation of the escapement mechanism which prevents further horizontal movement of the platen 35 and its frame, but also it prevents the completion of the stroke of any type bar of the machine, since the universal bar cannot be operated on account of its connection with the rocker dog 24. This is of importance 40 since it prevents more than a single impression being placed upon the paper at the time the platen reaches the end of the line, as predetermined by the adjustment of the margin stop B on the margin rack 47.

It frequently happens that the operator desires to allow the platen to travel somewhat farther than to the point determined by the position of the margin rack B. This is accomplished by the operator oscillating 50 the margin rack 47 by means of the finger piece 49, thereby swinging the finger 55 clear of the locking element C and permitting the latter to be returned to its normal position under the influence of the spring 55. The finger 55 of the margin stop B may 60 then travel toward the right a further distance, as viewed in Figures 1, 3 and 4. This distance ordinarily is three or four spaces and is determined by the finger 55 of the stop B coming into engagement with an outstanding horizontally disposed arm 65 on a stop plate D, which is rigidly fastened to the top of the rail 15 of the sub-frame 14, as shown in Figures 5 and 6.

Occasionally it is desired to allow the

platen to move still farther toward the right, as viewed in Figures 1, 3 and 4, and this can be accomplished by the operator oscillating the margin rack 47 so as to permit the finger 55 of the margin stop B to clear said arm 70 65. The platen and its frame may then move several teeth farther toward the right and the ultimate limit of movement is determined by a depending plate 66 carried by the frame 13 coming into engagement with 75 the end 67 of said stop plate D (see Figures 4 and 6).

The platen and its frame are limited in their movement toward the left, as viewed in Figures 1 and 2, by the finger 55 of the margin stop A coming into engagement with the end 68 of the laterally extended portion 65^a of the arm 65, as shown in Figures 2 and 6. Occasionally it is desired that the platen be moved still farther toward the left, as viewed in Figures 1 and 2, and to do this the operator oscillates the margin rack 47 so as to clear the finger 55 of the margin stop A from the end 67. The ultimate limit of movement of the platen and its frame 13 toward the left is then determined by another depending plate 69 fixed to the right-hand end of the frame 13, said plate 69 being adapted to engage with the shouldered end 70 of the stop plate D. 95

In actual practice, the shouldered end 67 of the stop plate D and the plate 66 carried at the left-hand end of the platen frame will be so adjusted that the ultimate limit of movement of the platen toward the right, which is shown in Figure 4, will occur when the rocker dog 24 and the stepping dog 31 are in the position shown in Figure 4—that is, when neither of the teeth 26 or 34 are in operative engagement with any tooth of the ratchet wheel and when the tooth 26 of the rocker dog is positioned over a tooth of the ratchet wheel 20. With this arrangement, it is evident that the rocker dog 24 cannot be oscillated or actuated from the universal bar of the machine, and, consequently, in this position of the platen, duplicate or multiple impressions cannot be placed upon the paper. 100 105 110

As will be evident from the preceding description considered in connection with the drawings, the escapement mechanism, the line locking element and the spring motor are all assembled on the one bracket 23, and, hence, may be applied as a unit to the sub-frame of the platen carriage. The other main element of the platen stop—that is, the stop plate D having the intermediate and ultimate stop shoulders, can readily be applied to the sub-frame and the necessary adjustment readily effected, thereby minimizing the cost of manufacture and assembling and facilitating adjustment and repairs. 115 120 125

I have herein shown and described what I now consider the preferred manner of car- 130

rying out the invention, but the same is merely illustrative and I contemplate all changes and modifications that come within the scope of the claims appended hereto.

5 I claim:

1. In a typewriting machine, the combination with a main frame, a longitudinally movable platen-carrying frame, and escapement mechanism including a ratchet wheel 10 and dog co-operable therewith; of a stop on said carrying frame; and means, located adjacent said dog and in the path of said stop, movable by said stop into the path of movement of said dog between the latter and the ratchet wheel to prevent operation thereof.
2. In a typewriting machine, the combination with a main frame, a longitudinally movable platen-carrying frame, and escapement mechanism including a ratchet wheel 20 and dog co-operable therewith; of a stop on said carrying frame; and a pivoted locking element, located adjacent said dog and in the path of said stop, movable directly by said stop into the path of movement of said dog to prevent operation thereof.
3. In a typewriting machine, the combination with a main frame, a longitudinally movable platen-carrying frame, and escapement mechanism including a ratchet wheel 30 and a rocker dog co-operable therewith; of a shouldered element mounted on said carrying frame; and means, located adjacent said dog and in the path of said shouldered element, movable by said shouldered element 35 into position between said dog and ratchet wheel to thereby prevent rocking of said dog.
4. In a typewriting machine, the combination with a main frame, a longitudinally movable platen-carrying frame, and escapement mechanism including a ratchet wheel and a dog co-operable therewith, said dog being operated from the universal bar of the machine and arranged to oscillate about an axis parallel to the line of platen movement; 45 of a shouldered element carried by said carrying frame; and a spring-influenced pivoted locking element in the path of movement of said shouldered element and adapted to be actuated by the latter to project said locking element into the path of oscillation of said rocking dog and thereby prevent further actuation thereof.
5. In a typewriting machine, the combination with a main frame, a longitudinally movable platen-carrying frame, and escapement mechanism including a ratchet wheel and a pivotally mounted rocker dog co-operable therewith; of a margin stop 50 justably mounted on said carrying frame; and a spring-influenced pivoted locking element located in the path of movement of said margin stop and adjacent said rocker dog, said locking element being directly engaged and movable by said margin stop

into the path of oscillation of said rocker dog to thereby prevent oscillation of the latter.

6. In a typewriting machine, the combination with a main frame, a longitudinally 70 movable platen-carrying frame, and escapement mechanism including a ratchet wheel and a rocker dog co-operable therewith, said rocker dog being oscillatable about an axis parallel to the line of movement of the platen; of a margin stop mounted on said carrying frame; and a spring-influenced pivotally mounted locking element located adjacent said dog and in the path of movement of said stop, said locking element being oscillatable about an axis perpendicular to the line of movement of the platen and adapted to be projected into the path of oscillation of said rocker dog between it and the ratchet wheel.

7. In a typewriting machine, the combination with a main frame, a longitudinally movable platen-carrying frame and escapement mechanism; of a margin stop mounted on said carrying frame; means co-operable with said margin stop to line-lock the platen; means for temporarily releasing the line-lock means to permit continued advancement of the platen-carrying frame; an intermediate fixed stop co-operable with said margin stop; and a final stop co-operable with a fixed part of said platen-carrying frame, said intermediate and final stops being formed on a single plate.

8. In a typewriting machine, the combination with a main frame, a longitudinally movable platen-carrying frame, and escapement mechanism; of right and left margin stops mounted on said carrying frame; a relatively fixed stop plate, said stop plate having right and left intermediate stop shoulders co-operable with said margin stops and provided also with right and left ultimate stops; and right and left means rigid with said carrying frame adapted to co-operate with said ultimate stops of said plate.

9. In a typewriting machine, the combination with a main frame, a longitudinally movable platen-carrying frame, and escapement mechanism; of right and left margin stops mounted on said carrying frame; a relatively fixed stop plate, said stop plate having right and left intermediate stop shoulders co-operable with said margin stops and provided also with right and left ultimate stops; right and left means rigid with said carrying frame adapted to co-operate with said ultimate stops of said plate; and a pivotally mounted margin rack 115 on which said margin stops are adjustably carried, said margin rack being oscillatable to clear the margin stops of said intermediate stops on said plate.

10. In a typewriting machine of the char- 130

- acter described, the combination with the main frame; of a removable platen carriage including a platen, a platen frame and a sub-frame; escapement mechanism carried by said sub-frame; line-locking means co-operable with said escapement mechanism and carried also by said sub-frame; and means on said platen frame for operating said line-locking means.
- 10 11. In a typewriting machine, the combination with a horizontally movable platen frame; of escapement mechanism co-operable with said frame, including a ratchet wheel and a rocker dog operable from the universal bar of the machine, said rocker dog having a tooth oscillatable into and out of engagement with the teeth of the ratchet wheel; a margin stop mounted on said frame; and a spring-influenced locking element pivotally mounted on the same axis as said ratchet wheel, said element having one portion thereof in the path of movement of said margin stop adapted to be actuated thereby and another portion adapted to be projected between said tooth of the rocker dog and the ratchet wheel whereby to prevent further oscillation of the rocker dog.
12. In a typewriting machine, the combination with a main frame, a platen-carrying frame movable horizontally, and escapement mechanism, including a ratchet wheel, a rocker dog and a stepping dog co-operable with the ratchet wheel; of a margin rack mounted on said carrying frame; and a spring-influenced locking element pivotally mounted on the same axis as that of the ratchet wheel, said element having one portion thereof in the path of movement of said margin stop and another portion adjacent said rocker dog and stepping dog but normally out of operative relation with respect thereto, said margin stop being adapted to actuate said element against the spring influence to thereby project said last named portion of said element between the rocker dog and the ratchet wheel.
13. In a typewriting machine, the combination with a main frame, a platen-carrying frame, and escapement mechanism including a ratchet wheel and a dog co-operable therewith; of a margin rack pivotally mounted on said carrying frame; right and left margin stops adjustably mounted on said rack; a relatively stationary stop plate having right and left intermediate stop shoulders and right and left ultimate stop shoulders, said intermediate stop shoulders being in the path of movement of said margin stops and the latter adapted to be freed therefrom by oscillation of the margin rack; right and left means on said carrying frame co-operable with said ultimate stop shoulders; and means, operable from one of said margin stops, to prevent actuation of said rocker dog.
- In witness that I claim the foregoing I have hereunto subscribed my name this 6th day of January, 1922.
- MAX GARBELL.
